UNITED STATES PATENT OFFICE.

CYRUS F. WICKER, OF WASHINGTON, DISTRICT OF COLUMBIA.

STAFF-GUN AND PROJECTILE THEREFOR.

1,198,398.

Specification of Letters Patent. Patented Sept. 12, 1916.

Application filed August 17, 1915. Serial No. 46,009.

To all whom it may concern:

Be it known that I, CYRUS FRENCH WICKER, a citizen of the United States, a resident of 917 Eighteenth street, Washington, District of Columbia, have invented a new and useful Improvement in Staff-Guns and Projectiles Therefor, of which the following is a specification.

With the modern method of trench warfare and their consequent use of hand grenades and shrapnel or bombs that are thrown only short distances, in most cases by hand, the necessity for a compact portable device for relieving the soldier of this tiresome task has arisen and the present invention is the result thereof.

With this and other objects in view, the invention consists in the combination, arrangement and construction of parts herein-after described and particularly pointed out in the claims, it being understood that I do not intend to limit myself to the details of construction of the various parts.

The invention is illustrated in the accompanying drawing in which—

Figure 1 shows a perspective view of the device in firing position. Fig. 2 is a sectional view of the upper end of the supporting member of staff with the projectile in firing position thereon. Fig. 3 is a sectional view showing a detail. Fig. 4 is a side elevation of my improved firing element.

In the drawings, 4 indicates a staff or the "gun" of my device, which is preferably made of metal of uniform diameter and made of such a size that one may be carried by each soldier. It is pointed at one end 5 which end is adapted to penetrate the ground 6 and a pivoted collar 7 having a sharpened flange 8 is provided on the staff 4 which will resist recoil of the explosions. At the upper end, the staff is hollowed out as at 9 so that a firing element 10 may be placed therein which will have a trigger mechanism 11 and a spring 12 co-acting therewith. I do not desire to be limited to the interior location of the firing mechanism nor to the particular trigger mechanism. The firing element consists of a stem 13 having or carrying a head 14 which is provided with a plurality of firing pins thereon.

My improved projectile is shown at 15 and consists preferably of a spherical ball having depending flanges 16 forming a re-

cess 17 therebetween. The ball may be either solid, a shrapnel, grenade, bomb or the like. The upper end of the staff 4 is adapted to neatly fit into the recess 17 and the flanges 16 to encircle the end of the staff 60 as shown in Fig. 2. Between the end of the staff and the ball 15 is a disk 18 of high explosive such as fulminate. A shield 19 may be added for the projectile 15 to prevent injury thereto by the explosion of the disk 18. 65

20 indicates a small pendulum or indicator pivoted to the staff adapted to cooperate with the scale 21 marked in yards.

The firing element 10 when in withdrawn position is firmly seated upon the gas tight 70 seat 22 formed therefor in the staff and in which position the pins of the element are just flush with the end of the staff or just enough therebelow not to render loading the gun dangerous. 75

In operation the staff is driven into the ground at the angle ordered. If the range is 200 yards, the soldier will hold the staff at an angle such that the pointer 20 points to 200 marked on the scale 21. The driving 80 element then takes place until the engagement of the collar 7 with the ground prevents any further driving. The collar 7 being pivoted will readily adapt itself to whatever angle the staff may be to the ground. The firing 85 element is locked in withdrawn position against its seat and then the projectile is fitted over the end of the staff 4 as shown in the drawings, the explosive disk first being placed on the end of the staff. To more 90 thoroughly protect the disk from accidental discharge it may be inclosed in paper or a punctural metallic casing of some kind. Then when it is desired to fire the projectile, it is only necessary to release the trigger 95 mechanism whereupon the firing element is forced upwardly by means of the spring pressure and the plurality of pins on the firing elements make explosion of the disk most positive. The explosion takes place, 100 as can be understood, at the very end and outside of the staff which gives the explosive the greatest possible surface to act upon. The depending flanges of the projectile in fitting over the end of the staff serve as the 105 guiding means for the projectile and also serve to confine the lateral pressure of the explosion which, however, is not great because of the principle outlined hereinbefore.

With the flanges of the shell notwithstanding 110

the lateral pressure instead of the gun or staff, the staff can be made decidedly lighter and therefore more readily portable by the soldier which is the object desired.

5. What I claim is:

1. In combination a rigid explosive disk and a staff gun including a firing element and a support for said disk encircling said element whereby said disk is supported directly adjacent to said element.
- 10 2. In combination, a staff gun comprising a staff having a chamber therein, a firing mechanism located in said chamber, and an explosive disk directly closing said chamber.
- 15 3. In combination, a staff gun comprising a staff having a chamber therein, a firing mechanism located in said chamber, and a

rigid explosive disk directly closing said chamber.

4. In a staff gun, an annular end explosive support, a firing element encircled by said support, and a gas tight seat for said firing element.

5. In a staff gun, an annular end explosive support, a firing element encircled by said support, and a complementary conical seat for said firing element.

6. In combination, a rigid explosive disk, a staff gun including a support for said disk and a reciprocating firing element, and means for maintaining said disk directly on its support against the action of the firing element.

CYRUS F. WICKER.
